UNITED STATES PATENT OFFICE.

CARL W. WEISS, OF NEW YORK, N. Y., ASSIGNOR OF ONE-HALF TO
AUGUST MIETZ, OF SAME PLACE.

ENGINE.

SPECIFICATION forming part of Letters Patent No. 651,317, dated June 5, 1900.

Application filed January 16, 1899. Serial No. 702,238. (No model.)

To all whom it may concern:

Be it known that I, CARL W. WEISS, a citizen of the United States, residing in the city of New York, in the county and State of New York, have invented certain new and useful Improvements in Engines, of which the following is a specification, reference being had to the accompanying drawings, forming a part hereof.

10 This invention is concerned with the feeding or delivery of the hydrocarbon or other fuel which forms the basis of the charge in explosive-engines.

The improvement is particularly applicable 15 to multiple engines—that is to say, to machines having two or more engines coupled together, so that they shall work in synchronism, as when coupled directly to a common crank-shaft—while the other feature of the 20 invention referred to is capable of a wider application and is not restricted to engines of this particular type. In multiple explosive-engines it is practically impossible to provide independent feeding or feed-regulating 25 devices for the several cylinders which shall be perfectly synchronous in their action, the result being that a major portion of the work is performed by one engine and the highest possible efficiency is not attained.

30 The object of this invention is to provide a single feeding or a feed-regulating device (it being intended to include feed-governing mechanism as well as fuel-delivery mechanism) common to the several single engines 35 and having such an operative relation therewith that the hydrocarbon or other fuel is delivered or admitted to each working cylinder at the same relative point in its cycle as in the case of the other cylinder or cylinders, 40 whereby each single engine performs its proportion of the work and the maximum efficiency is attained. The mechanism in which the invention, as described hereinafter, is embodied is free from complication, and in its 45 operation effects the delivery of the hydrocarbon or other fuel into each working cylinder at the instant when the conditions within that cylinder are favorable to its introduction. The character of the expanding fluid from 50 which the piston receives its forward impulse is immaterial so far as concerns that portion

of the invention which relates to the exhaust; but all of the features of the invention are illustrated in the accompanying drawings and described hereinafter as embodied in a 55 duplex explosive-engine of a well-known type, in which oil is delivered to each working cylinder to form the basis of an explosive charge.

In the drawings, Figure 1 is a plan view of a duplex explosive-engine to which the improvements are applied. Fig. 2 is a view, partly in elevation and partly in vertical central section, of one of the single engines. Fig. 3 is a detail view in section of the fuel-discharge nozzle. Fig. 4 is a detail view in 65 section of the pump with its valves.

In the construction illustrated in the drawings there are two working cylinders A, having each a piston B, connected by a pitman B' with a common crank-shaft C, the latter 70 having an electric generator C' mounted thereon between the two single engines; but it will be obvious that a greater number of single engines might be coupled together by a common crank-shaft or otherwise and that the 75 force of the engine may be transformed into other forms of work than the development of electrical energy. The devices for vaporizing the oil and for igniting the vapor may be 80 of any usual or suitable character and need not be described herein.

The device which regulates the delivery of the hydrocarbon or other fuel is shown as a cylinder g, which is connected with a supply vessel G' and with a delivery-orifice, as H, 85 in each working cylinder. A plunger G within the pump-cylinder effects the delivery and is operated as many times during the complete cycle of the multiple engine as there are single engines coupled together—that is 90 to say, in the construction represented in the drawings, in which two single engines are coupled to the common crank-shaft one hundred and eighty degrees apart, the pump is operated twice for each rotation of the crank-shaft. Any suitable mechanical devices 95 may be employed for effecting the operation of the feeding device as many times as may be required. As represented in the drawings, an eccentric C' is mounted on the crank-shaft, and its rod C² is connected to the middle joint of a pair of toggle-levers C³. One end of the pair 100

of toggle-levers is pivoted at a fixed point, and the other is connected to one end of a bell-crank lever c' . It will be seen that the forward movement of the eccentric-rod rocks the bell-crank lever, as does also the return movement, so that the bell-crank lever receives two movements for each rotation of the crank-shaft. A rod c^2 is connected to the lever c' and carries a flat-faced nut c^3 , which rests upon an incline c^4 . When the engine is running at normal speed, the end of the rod c^2 strikes the end of a tongue f , which is operatively connected with the pump-plunger and actuates the same; but when the engine is running too fast the momentum of the rod and the nut as the latter travels up the incline will throw the end of the rod above the end of the tongue and the plunger will be unaffected. A retarder may be carried by an arm extended from the bell-crank, as indicated at c^5 , to bear upon the rod c^2 and prevent the same from flying up too far when the engine is running very fast.

As before stated, the pump-cylinder is connected with the several single engines and the effective movement of the pump or other feed-regulating devices is so arranged in the particular construction shown as to take place as each engine-piston reaches the forward limit of its stroke, at which time the exhaust-port a' has been opened by the forward movement of the piston B beyond it and the pressure in the engine-cylinder has fallen practically to zero, so that there is no back pressure to resist the flow of the oil, which is then delivered into the cylinder. At the same instant the pressure in the other engine cylinder or cylinders is sufficiently great to shut off the delivery of oil into the same. It follows, therefore, that the oil or other fuel is delivered only into that cylinder which is in readiness to receive it and at the instant when it is required. Each engine receives the impulse of the exploding charge in turn and performs its share of the total work. The injection or delivery of the fuel does not necessarily take place at the instant of the opening of the exhaust; but as the fuel follows from the regulating device the path of least resistance both cylinders may be under pressure, though not under the same pressure.

The nature of the invention and the mode

of operation of its several features will now be readily understood without further explanation herein. It will also be understood that the invention is not limited to the precise construction and arrangement of parts shown and described herein.

I claim as my invention—

1. In a multiple-cylinder explosive-engine having several single engines coupled together, a single fuel-feed connected to the several engines in common, means for operating said fuel-feed once for each single engine during a complete cycle of the multiple-cylinder engine, and a governor to control the action of said feed, the charge at each operation of the feed being delivered to that engine in which the pressure is lowest.

2. In a multiple-cylinder explosive-engine having several single engines coupled together, each of said single engines having an exhaust-port and means to open the same, a single fuel-feed connected to the several engines in common, means for operating said fuel-feed as the exhaust-port of each single engine is opened, and a governor to control the action of said fuel-feed, the charge at each operation of the feed being delivered to that engine in which the pressure is lowest.

3. In a multiple-cylinder explosive-engine having a common crank-shaft and several single engines coupled thereto at different points, a single fuel-feed connected to the several engines in common, means for operating said fuel-feed once for each single engine during each complete rotation of said shaft, and a governor to control the action of said feed.

4. In a multiple-cylinder explosive-engine having a common crank-shaft and several single engines coupled thereto at different points, each of said single engines having an exhaust-port opened by the piston as it reaches the limit of its forward stroke, a single fuel-feed common to the several engines, means for operating said feed as the exhaust-port of each single engine is opened, and a governor to control the action of said feed.

This specification signed and witnessed this 9th day of January, A. D. 1899.

CARL W. WEISS.

In presence of—

ANDREW H. SCOBLE,
F. M. EGGLESTON.
